UNITED STATES PATENT OFFICE.

EMIL MENGER, OF WIESBADEN, GERMANY.

GASIFYING BURNER FOR LIQUID FUEL.

Application filed August 3, 1921. Serial No. 489,615.

To all whom it may concern:

Be it known that I, EMIL MENGER, a citizen of the Republic of Germany, residing at Viktoriastr. 14, Wiesbaden, Germany, have 5 invented certain new and useful Gasifying Burners for Liquid Fuel (for which I have filed application in France October 13, 1919), of which the following is a specification.

10 Heating by means of liquid or liquefiable fuel has a tendency to become generalized owing to the increased scarcity of coal and other solid fuel and therefore to their high prices.

15 On the other hand, liquid fuels are not found in the natural state in all countries. It has been tried and succeeded to extract from coal tar secondary products such as tar oil, naphthalene, residues of anthracite 20 and other fuel of the same kind, the extraction of which is effected in large quantities and the cost price of which is very small.

With the apparatus used at present for the combustion of oil and more particularly 25 of raw naphthalene, the gasification of the fuel is defective owing to the difficulty of maintaining in these apparatus the naphthalene in the liquid state which condition is essential for permitting its use in the same 30 manner and with the same advantages as the tar oil.

The gasifying burner which is the object of the present invention is intended to remedy the above drawbacks by effecting a 35 previous heating of the fuel which is thus constantly maintained in the liquid state, ensuring its gasification and its complete combustion.

The invention is illustrated by way of example in the accompanying drawings in which:

Fig. 1 is a longitudinal section of the whole of the burner-gasifier, more especially intended for the treatment of raw naphthalene.

Fig. 2 shows separately on a larger scale the sprayer device, seen from the side.

Fig. 3 is a corresponding plan view.

Fig. 4 is a modification of construction.

50 Fig. 5 shows in longitudinal section the details for mounting a box for the air inlet for a gasifying-burner of oil.

Fig. 6 is a front outside view, the air conduit occupying a different position.

55 Fig. 7 is a longitudinal section along the line A A of Fig. 6.

Fig. 8 is a front view of the whole of the gasifying-burner in which the box for the air inlet can be taken to pieces, and

Fig. 9 is a horizontal section thereof.

Referring to Fig. 1 of the drawings, the gasifying-burner comprises an outer cylindrical casing 1 which is horizontal and is prolonged at one end by a cylindrical body 2 forming two chambers 3 and 4 separated by a middle partition 5 and in which two valves 6 and 7 are arranged. The outside casing is connected to a pipe for the air inlet 8 mounted on a fan and on which rests and is fixed at its basis the cylindrical body 2.

A box 9 is mounted inside the casing and communicates with the chamber 3 by means of an orifice 10 provided at the lower part and coming opposite the flange 6.

The combustible is led into the apparatus by means of a conduit engaging at one end in the box 9 in which it is fixed. The said conduit comprises an outside casing 11 extended by a vertical base 12 and surrounding an inner body 13 in such a manner as to form an annular chamber 14 between the said two members the said chamber opening through conduits 15 and 16 at the lower part of the base 12 and at the upper part of the chamber, the said conduit being connected on the other side to a steam generator.

The fuel passes into a channel 17 provided at the centre of the base 12 and leading to another channel 18 provided in the middle part of the body 13.

The quantity of liquid coming from the channel 17 and penetrating into the channel 18 is adjusted by means of a screw-spindle 19 operated from the outside by means of a hand wheel 20 provided with a pointer which is moved opposite a graduated sector.

The end of the channel 18 opening into the box 9 is screw-threaded so as to receive the sprayers 21 provided with a connection 22 connecting its screw-threaded part to a member 23 ended by a fork the two tubular branches 24 of which (see Fig. 3) are flattened in the form of a cone at their free end in order to have outlet orifices 25 of small diameter with a view to increasing the outlet speed of the liquid fuel or of the gas.

The tubular branches 24 are extended by flattened surfaces 26, the widened ends of which are cut so as to form, by bending the metal, vertical partitions 27 perpendicular to the horizontal plane of the surfaces 26.

The latter may moreover be embossed so as to form pockets 28 as shown in Fig. 4.

The device which has been described works in the following manner:

5 The raw naphthalene is led into the apparatus through a channel 17 and penetrates into the channel 18 in a quantity which is determined by the screw spindle 19.

10 The steam penetrates at the same time through conduits 15 and 16 into the annular chamber 14 surrounding the central body 13 and effects the heating of the channel 18 thereby producing an intense vaporization of the raw naphthalene circulating in the 15 said channel.

15 The gas or vapour of naphthalene leaving the channel 18 passes into the nozzle 23 and is distributed in the two tubular branches 24 of the sprayer 21. The said branches have 20 a smaller section at their end owing to their conical shape, therefore an increase of speed is produced at the outlet of gas through the orifices 25 and the said gas slides on the surfaces 26 in order to abut against the 25 vertical partitions 27. The shock of the gas against the partitions produces a complete spraying of the fuel, the intimate mixture of which with the atmospheric air brought by the valve 6 into the chamber 3 30 and afterwards into the box 9 forms an inflammable combustible fluid, the length of the flame being adjusted by a flap 7 of the chamber 4.

35 In gasifiers for oil burner, the regularity of work depends mainly on the arrangement of the box bringing air to the oil conduit. As the mounting of the said two conduits depends on the local circumstances of the plant, it is absolutely necessary to make the 40 box for the air inlet capable of being taken to pieces in order to be able to position it in the chamber of the gasifier according to the position of the air conduit in such a manner as to prevent the oil from penetrating 45 into the said conduit in case that the screw spindle would not ensure a regular flow of oil.

To this end, the end of the outer casing 1 forming a flange on which is mounted the 50 box 9, is provided with fixed bolts 29 (see Figs. 5, 6 and 7) in a variable number corresponding to notches 30 provided on the periphery of the flange of the box 9.

55 According to the position of the conduit of air inlet on which is branched the valve chamber of the outer casing 1, the box 9 may be positioned by rotating it around itself and by bringing one or the other of the notches 30 opposite fixed bolts 29 in such a manner that the orifice 10 for the inlet of air shall be situated in the diametrically opposite direction to that of the conduit for the inlet of air, the said orifice being situated at the upper part of the box 9 as illustrated in Fig. 5 when the conduit for the air 60 65

inlet is arranged below the casing and at the lower part of the box as illustrated in Fig. 7 when the conduit is arranged above the casing.

The said variation in the arrangement of 70 the box 9 allows of avoiding in the case when the valve would not work normally, the oil from penetrating into the air conduit and the accidents which could result therefrom, owing to the inflammable nature 75 of the mixture.

Lastly, the box for the air inlet of the gasifiers more especially used for hardening or melting furnaces may be rendered capable of being taken to pieces with the corresponding oil conduit during the operation. In this case arms 31 are mounted upon fixed bolts 29 of the ears of the outer casing 1, said arms being maintained on the bolts by means of a nut permitting them to pivot. 80 85

The said arms are prolonged by heels 32 which, when the arms are horizontally placed bear upon the flange of the box 9 in such a manner as to keep it applied against the flange of the outer casing. 90

The oil is brought into the box 9 through a flexible pipe 33 mounted on the lateral wall of the box and leading to the sprayer 21 in such a manner as to render the said pipe 33 flexible and the sprayer 21 integral 95 with the box 9 and regulating spindle 19 operated by its hand wheel 20.

In order to take to pieces the box 9 and members with which it is provided during the operation, it is therefore enough to reverse the two lever arms 31 as shown by the mixed lines in Fig. 8 by pivoting them on bolts 29 in such a manner that their heels 32 disengage the flange of the box 9; it is then easy to seize the hand wheel 20 and to pull out the whole of the box 9 so as to make it leave the apparatus together with the oil conduit 33 and the sprayer 21. 100 105 110

From what precedes, it is seen that gasifiers thus constructed have numerous advantages. Their adjusting is obtained with rapidity and with the greatest precision. The quantity of air which is necessary for the mixture of the fuel is adjusted with a precision such that the mixture is completed 115 and does not produce any smoke or soot.

Excessively fine spraying is always ensured whatever the quantity of fuel brought into the apparatus may be. Lastly, the fuel flows automatically into the burner under its natural pressure so that neither an obstruction nor a stopping can be produced. 120

What I claim is:—

1. A gasifying burner for liquid fuel, comprising an outer casing, two chambers in the said outer casing, an air inlet pipe communicating with the said two chambers, regulating valves for controlling the communication between the said air inlet pipe and the said two chambers, a mixing cham- 125 130

ber arranged inside the outer casing for the liquid fuel and atmospheric air, an orifice provided in the wall of the mixing chamber communicating with one of the chambers that communicates with the air inlet pipe, a conduit for admitting fuel to the mixing chamber, an annular heating jacket surrounding the said fuel admission conduit, a screw spindle for regulating the feed of fuel to the conduit, means provided on the said spindle for operating it from the outside, a sprayer fixed on the inner end of the fuel admission conduit, the said sprayer comprising two tubular flattened nozzles having tapering ends for increasing the outlet speed of the fuel, surfaces extending from the nozzles and vertical partitions on the said surfaces for dividing up the fuel.

2. A gasifying burner as claimed in claim 1, having a flange on the mixing chamber

serving for mounting the latter upon the outside casing, notches on the periphery of the said flange, fixed bolts on the outside casing intended to engage with the said notches, whereby the mixing chamber can be positioned relatively to the chamber which communicates with both the inlet pipe and the mixing chamber, in such a manner that the orifice in the wall of the mixing chamber which establishes the communication with the said chamber lies on the side diametrically opposite to that of the air inlet conduit.

In testimony whereof I have signed my name to this specification.

EMIL MENGER.
